UNITED STATES PATENT OFFICE.

JULIUS STRELITZER, OF NEW YORK, N. Y.

DISH-WASHER.

SPECIFICATION forming part of Letters Patent No. 735,840, dated August 11, 1903.

Application filed June 19, 1901. Serial No. 65,106. (No model.)

To all whom it may concern:

Be it known that I, JULIUS STRELITZER, a citizen of the United States, and a resident of New York city, in the county of New York and State of New York, have invented certain new and useful Improvements in Dish-Washers, of which the following is a specification.

This invention relates to an improvement in apparatus for washing dishes, and particularly to one wherein hot water is employed in fine jets to remove from the dishes all extraneous matter.

The object of the invention is to construct an apparatus for the above purpose which will wash thoroughly a large number of dishes in a minimum space of time and which through the medium of hot water alone will not only wash them, but will effect the perfect drying thereof.

With this object in view the invention consists in the construction, combination, and arrangement of parts, as will be hereinafter fully described and claimed.

In the accompanying drawings, which form a part of this specification, Figure 1 represents in sectional elevation my improved dish-washer; and Fig. 2 represents a horizontal section thereof, taken in the plane indicated by the line 2 2, Fig. 1.

The casing 3 may assume various forms and proportions; but I prefer to make it substantially of the shape and proportions illustrated, a closely-fitting door being provided therefor, as indicated at 4. The casing may be made of any suitable material—for instance, sheet iron or copper.

Within the casing 3, and preferably at the middle of the ends, there are stand-pipes 5 and 6, from which extend headers 7 at intervals and between which headers extend horizontal perforated pipes 8. These horizontal perforated pipes form shelves for the reception of trays holding the dishes to be washed.

The hot water may be conveyed to these stand-pipes in any suitable way, preferably by pipes, as 9 10, which lead to the stand-pipes 5 6, respectively, from a tank, as 11, which for convenience may be located on top of the casing 3, the water being led into the tank 11 from any suitable boiler, as by means of the pipe 12. By this arrange-

ment of pipes an equal flow and pressure may be had in both stand-pipes, and the tank 11 assists in keeping said flow even, because of 55 a cushion of steam which will be present in said reservoir while the apparatus is in operation.

When the apparatus is not in use, the water from the reservoir 11 may be drawn off 60 by means of cock 13, which for convenience may discharge into the chamber 3, whence the water flows to the sewer through outlet-pipe 14. The flow of water to the tank or reservoir 11 is controlled by the cut-off 15, 65 and the flow of water from the tank through pipes 9 and 10 is controlled by the cut-offs 16 and 17.

It is often desirable to wash a small number of dishes and not to use the entire apparatus for so doing. This I accomplish by dividing the stand-pipes 5 and 6 vertically, as by cut-offs 18 and 19, which is a convenient plan of subdivision, though any other plan may be followed to accomplish the purpose. 75

In using the apparatus the trays or racks of dishes are deposited on the shelves formed by the perforated pipes 8, the door closed, and the water turned on by opening the cut-off 15. Then if it is desired to use the entire apparatus the cut-offs 16 and 17 are opened, when from the perforations of the pipes 8 of all the shelves there will be projected fine streams of water, and these striking the dishes wash them thoroughly. In thus washing them they 85 are heated sufficiently to insure the speedy evaporation of all drops of water that may cling to them after the washing is completed. The apparatus full of very dirty dishes can be thoroughly cleaned in two minutes. The 90 cut-offs 18 and 19 are also preferably open when the entire apparatus is in use, since thereby an even pressure and flow of water is maintained in both sets of headers, and therefore at both ends of and throughout the 95 pipes 8.

To use the upper or lower part of the apparatus alone, the cut-offs 18 and 19 will be closed and the cut-off 16 or 17 used, as the case may be. The water and dirt from the dishes 100 are readily discharged through the pipe 14, which preferably leads to the sewer through the usual trap.

The trays for the dishes are preferably

built as open as possible to afford the most complete access of the streams of water to the dishes, and the perforations in the pipes 8 are as small as will permit the flow of solid 5 streams and are so close that the water of adjacent streams when they strike the dishes will coalesce, thereby insuring the thorough and forcible drenching of the entire surface of each dish. Said perforations are also preferably arranged in spirals about the tubes 8, as indicated in Fig. 2, though they may be arranged in circles, if desired, as indicated in Fig. 1.

Many changes may be made in the construction and formation of parts aside from those mentioned without departing from the invention.

I claim as my invention—

1. In a dish-washer, the combination with a 20 closed chamber of a stand-pipe in each end thereof, headers branching from each stand-pipe, a number of horizontal perforated pipes extending from one header at one end to the corresponding header at the other end and 25 forming shelves for dish-trays, and means for controlling the flow of water to each stand-pipe and into and through the perforated pipes from each end.

2. In a dish-washer the combination with a 30 closed chamber of a stand-pipe in each end thereof, headers branching from each stand-pipe, a number of horizontal perforated pipes extending from one header at one end to the corresponding header at the other end and 35 forming shelves for dish-trays, a pipe leading from a suitable source of hot-water supply to each header, and cut-offs in said supply-pipes and cut-offs in the stand-pipes, as and for the purpose set forth.

3. In a dish-washer the combination with a 40 closed chamber of a stand-pipe in each end thereof, headers branching from each stand-pipe, horizontal perforated pipes extending from one header at one end to the corresponding header at the other end and forming 45 shelves for dish-trays, a pressure-tank, a pipe leading from a source of hot-water supply to said tank, pipes leading from the tank to each of said stand-pipes and cut-offs in said pipes for controlling the flow of water through the 50 perforated pipes.

4. In a dish-washer the combination with a closed chamber of a stand-pipe in each end thereof, headers branching from each stand-pipe, horizontal perforated pipes extending 55 from one header at one end to the corresponding header at the other end and forming shelves for dish-trays, a cut-off in the middle of each header, a hot-water-supply pipe connected to one header below the cut-off therein, and another hot-water-supply pipe connected to the other header above the cut-off therein, as and for the purpose set forth.

5. An apparatus for the purpose specified comprising a casing having a fluid-outlet 65 therein, a source of fluid-supply, a rack arranged within said casing having perforated shelves, and communicating with the source of fluid-supply, and valve mechanism for supplying fluid to a part of said perforated 70 shelves, substantially as specified.

Signed at New York, in the county of New York and State of New York, this 12th day of June, A. D. 1901.

JULIUS STRELITZER.
